COMBINATION OUTDOOR TABLE
AND CLOTHESLINE

Elwood S. Hannameyer, Aptos, Calif.

Application May 24, 1950, Serial No. 163,932

6 Claims. (Cl. 211—119.01)

1

This invention is directed to, and it is an object to provide, a combination outdoor table and clothesline; a prime feature of the invention being the concealment in the table of the clothesline when not in use.

Another object of the invention is to provide a combination outdoor table and clothesline, as above, wherein the clothesline can be brought into position for use readily and conveniently by hand; the clothesline when so disposed having relatively long, multiple lines sufficient to hang a considerable amount of laundry.

A further object of the invention is to provide a combination outdoor table and clothesline wherein a portion of the table top is adapted to be erected as a mast having a cross arm, and the multiple lines being carried on a drum within the table; such lines, when the mast is erected, running from the drum over the cross arm and thence spanning to a cross bar detachably secured to an anchor element at a remote point.

An additional object of the invention is to provide a combination outdoor table and clothesline which is designed for ease and economy of manufacture; the design being neat and attractive in appearance.

Still another object of the invention is to provide a practical and reliable combination outdoor table and clothesline, and one which will be exceedingly effective for the purpose for which it is designed.

These objects are accomplished by means of such structure and relative arrangement of parts as will fully appear by a perusal of the following specification and claims.

In the drawings:

Fig. 1 is a perspective view of the table with the clothesline in its concealed, out-of-use position.

Fig. 2 is a similar view, but shows the clothesline in use.

Fig. 3 is an enlarged fragmentary, sectional elevation of the table with the clothesline parts in concealed, out-of-use position.

Fig. 4 is a similar view, but shows the clothesline parts in position of use.

Fig. 5 is an enlarged, fragmentary and sectional elevation showing the holding ratchet assembly for the clothesline drum.

Referring now more particularly to the characters of reference on the drawings, the novel, combination outdoor table and clothesline comprises a table, indicated generally at 1, which is of outdoor or patio type, preferably fabricated of wood and having an attractive appearance.

The table 1 includes a rectangular base frame 2 supported, at opposite ends, by axles 3 carrying ground engaging wheels 4.

Legs 5 upstand from the rectangular base frame 2 and support a table top, indicated generally at 6, which top includes sides 7 and ends 8.

A portion of the table top 6 is comprised of a separate T-shaped mast, indicated generally at

2

9, said mast including a post 10; the mast normally being in a down, flush position to serve as part of the table top, as in Fig. 1.

Adjacent but short of its lower end, i. e. the end opposite the cross arm 11, the mast 9 is hinged, as at 12, to a cross member 13 for erection to a perpendicular position from the aforesaid normally down, flush position.

A guided pull cord 14 is connected at one end to the lower end of the post 10 and at the other end to a loaded pull spring 15; the arrangement being such that said pull spring acts on the cord 14 in a direction tending to erect the mast 9, which erection is normally prevented in the manner which will hereinafter appear.

A transverse drum 16 is journaled in the table in a position directly below the cross arm 11 when the mast 9 is in its down, flush position, and said drum 16 includes a shaft 17. A hand crank 18 is adapted to releasably fit one end of the shaft 17 outwardly of the corresponding side 7 of the table top.

A plurality of lines 19 are secured to, and wound about, the drum 16 in spaced-apart relation, and from the drum the lines extend through corresponding guide eyes 20 on the inner side of the adjacent end 8.

From the guide eyes 20 the lines 19 pass through corresponding guide openings 21 of a plate 22 which is secured to and projects outwardly of the cross arm 11.

Beyond the plate 22 the lines 4 are secured to a cross bar 23.

When the clothesline is not in use, with the T-mast 9 in its down position, and with the lines 19 wound onto the drum 16 as far as possible, the cross bar 23 abuts the plate 22 and lies alongside the cross arm 11 in the manner shown in detail in Fig. 3. In this position the cross bar 23 underlies a transverse cover or flap 24 hinged, as at 25, for motion to an open position from a normally closed position. When the cover 24 is closed it matches with the cross arm 11 to form a flush part of the table top 6.

The transverse cover 24 is normally maintained in its closed position by a hook and eye 26.

The drum 16 is normally prevented against rotation in a line-unwinding direction by a pawl and ratchet unit which includes a ratchet wheel 27 on the shaft 17, and a pawl 28 cooperating in holding relation with said ratchet wheel; the pawl 28 being releasable by a finger lever 29 accessible outwardly of one of the sides 7.

When it is desired to use the clothesline, the table is secured against rolling movement by engaging an anchor peg 30 in the ground. Thereafter, the cover 24 is opened and the pawl 28 released by finger motion of the lever 29. Upon release of the pawl 28 the pull spring 15 acts to erect the mast 9.

Thereafter, with the pawl 28 remaining released, the cross bar 23 is carried to a remote point, unwinding the lines 19 from the drum

16 and pulling them through the guide plate 21. The cross bar 23 is then anchored to the side of the house, a tree, or the like, by engaging said cross bar on a hook 31. In this position of adjustment the clothesline is ready for use and provides sufficient line length for a substantial quantity of laundry.

When use of the clothesline is completed, the cross bar 23 is detached from the hook 31 and the lines 19 are wound onto the drum 16 by actuating the latter through the medium of the hand crank 18.

As the lines wind onto the drum 16, cross bar 23 will abut the plate 22, and continued winding pulls the mast 9 to its down, flush position, whereupon the described pawl and ratchet unit acts to prevent undesired rising of the mast. After the parts are returned to the above position of non-use the transverse cover 24 is closed so that the table then completely conceals the clothesline arrangement.

At the end of the table opposite the drum 16 there is a bin 32 for clothespins; such bin normally being closed by a transverse cover 33 hinged as at 34.

The described outdoor table and clothesline provides a very practical and reliable structure for the intended dual purposes; the table, including the clothesline arrangement, being convenient to use, and readily adjusted between its respective positions of use.

From the foregoing description it will be readily seen that there has been produced such a structure as substantially fulfills the objects of the invention, as set forth herein.

While this specification sets forth in detail the present and preferred construction of the structure, still in practice such deviations from such detail may be resorted to as do not form a departure from the spirit of the invention, as defined by the appended claims.

Having thus described the invention, the following is claimed as new and useful, and upon which Letters Patent are desired:

1. A combination outdoor table and clothesline, comprising a table including a top, a portion of said top being mounted for erection as a mast, a drum mounted in the table, and a clothesline on the drum adapted to unwind therefrom, extend to the mast, and thence span to a remote anchor point.

2. A combination outdoor table and clothesline, comprising a table having a top, a portion of said top being a separate T-shaped mast including a post and a cross arm, means mounting the mast for erection from a normally, down, flush position, a transverse drum mounted in the table under the top and adjacent said cross arm, and a plurality of spaced lines on the drum adapted to unwind therefrom, extend to the cross arm when the mast is erected, and thence span to a remote anchor point.

3. A combination outdoor table and clothesline, comprising a table having a top, a portion of said top being a separate T-shaped mast including a post and a cross arm, means mounting the mast for erection from a normally, down, flush position, a transverse drum mounted in the table under the top and adjacent said cross arm, a plurality of spaced lines on the drum, said lines being slidably guided on the cross arm of the mast, and a cross bar to which the lines connect beyond the cross arm; the lines, when the clothesline is in use and the mast erected, extending to the cross arm from the drum, and

thence spanning to the cross bar anchored at a remote point.

4. A combination outdoor table and clothesline, comprising a table having a top, a portion of said top being a separate T-shaped mast including a post and a cross arm, means mounting the mast for erection from a normally down, flush position, spring means connected between the table and mast tending to erect the mast, releasable means normally preventing erection of the mast, a transverse drum mounted in the table under the top and adjacent said cross arm, and a plurality of spaced lines on the drum adapted to unwind therefrom, extend to the cross arm when the mast is erected, and thence span to a remote anchor point.

5. A combination outdoor table and clothesline, comprising a table having a top, a portion of said top being a separate T-shaped mast including a post and a cross arm, means mounting the mast for erection from a normally down, flush position, spring means connected between the table and mast tending to erect the mast, a transverse drum mounted in the table under the top and adjacent the cross arm, a plurality of lines on the drum adapted to unwind therefrom, guide means on the cross arm through which the lines slidably extend, a cross bar to which the lines connect beyond the cross arm, the cross bar normally abutting the cross arm but being adapted to be anchored at a remote point when the mast is erected and the lines unwound and run out for use, a hand crank adapted to rotate the drum to wind the lines thereon and to cause folding of the mast to said flush position upon engagement of the cross bar with the cross arm and continued winding of the lines on said drum, and a releasable pawl and ratchet unit cooperating with the drum normally preventing unwinding of the lines therefrom.

6. A combination outdoor table and clothesline comprising a table having a top, a portion of said top being a mast which includes a post and an outer-end cross arm, means mounting the mast for erection from a normally lowered flush position, a drum mounted in the table under the top adjacent the cross arm, a plurality of lines on the drum adapted to unwind therefrom, a plate projecting from the outer and under side of the cross arm having openings through which the lines are guided, a cross bar separate from the cross arm on which the lines at their outer end are secured, the cross bar resting on the plate when the mast is in its lowered position and being thinner than the cross arm, and a flap forming part of the table top, hinged on the table beyond the cross arm and arranged when swung down to lie flush with and substantially abut against the cross arm and to cover said cross bar.

ELWOOD S. HANNAMEYER.
